PIPE ASH EJECTOR

John Di Federico and Norman S. Di Lorenzo,
Southbridge, Mass.

Application August 4, 1949, Serial No. 108,644

6 Claims. (Cl. 131—183)

1

This invention relates to pipes having ash and heel ejectors and the principal object of the invention resides in the provision of a pipe having a bowl and there being an upstanding bushing or the like therein, said bushing forming a well in the body of the pipe and slidably receiving a push rod having thereon a flexible steel ash and heel ejection plate and including an ejector handle which is normally adapted to lie under a part of the pipe in substantially housed condition, but which may be swung around on a pivot on the ejector plunger to operate the same rectilinearly to eject material from the bowl of the pipe.

Further objects of the invention include the provision of a pipe as above stated including a cover firmly secured to the plunger and covering the bushing so as to prevent entrance of tobacco juice and particles thereto; the provision of the device as aforesaid including a heat resisting rubber shield forming a tight but flexible closure completely preventing the entry of tobacco juice and particles to the plunger; and the provision of a pipe of the class described having a slotted ash ejector plate, the same being flexible and adapted to be movable in the pipe even though it should tend to stick.

Other objects and advantages of the invention will appear hereinafter.

Reference is to be had to the accompanying drawing in which:

Fig. 1 is a central longitudinal sectional view through a pipe according to the present invention;

Fig. 2 is a top plan view thereof;

Fig. 3 is a fragmentary view in elevation;

Fig. 4 is an enlarged sectional view illustrating the ash ejector plunger;

Fig. 5 is a top plan view of the plunger;

Figs. 6 and 7 are detailed views of the plunger and handle; and

Fig. 8 is an enlarged view in section showing a ball catch for the handle, said ball catch maintaining the same in housed condition shown in Fig. 3.

In carrying out the present invention, there is provided a more or less conventional pipe stem 10 which fits into the body 12 of the pipe and which may be held therein by a bushing 14. The body 12 is preferably molded plastic, but may be any suitable material, such as wood, metal, etc.

The body 12 is provided with a bottom longitudinal slot 16 which is adapted to at least partially house a lever or handle 18 which extends rearwardly and is pivoted at 20 to a plunger 22 extending vertically in upright condition in a

2

bushing 24 which may be formed as a part of the body 12 and provides therewith an annular well 26. The bushing 24 is here shown as made up of two parts fitted together, and is provided with screw threads 28 which mesh with like screw threads on a bowl 30. The portion of the bushing containing the screw threads 28 is cut out as at 32 to allow the passage of smoke from the bowl of the pipe down into the well 26, and a gasket 33 may be used between the bowl and the body 12.

The plunger 22 is provided at its upper end with a cover 34, this cover being shown in detail in Fig. 4. The plunger 22 is surrounded by a compression spring 36 which provides for correct alignment of the plunger in the bushing 24 during the ejecting action, i. e., reciprocation of the plunger. It is to be noted that this spring has been inverted in Fig. 4 as compared with the Fig. 1 showing thereof, and the spring may be assembled in the device in either way. Also, this spring may be made of thicker or thinner wire depending on choice or design, as illustrated in Figs. 1 and 4.

Above the cover there is provided a thin flexible stainless steel element 38. This element is slotted radially as at 40, see Fig. 5, for the purpose of increasing the flexibility thereof so that if it sticks in the bowl, it may, nevertheless be pushed up to complete the cleaning action. The diameter of the element 38 is slightly less than that of the bowl of the pipe.

A heat resisting rubber shield 42 may be sealed to the cover 34 as at 44 and to an upstanding boss at the bottom of the recess provided by bushing 24, see 46 in Fig. 4, but this shield may be omitted as shown in Fig. 1. A form of silicon rubber is usable for the purposes stated, and the shield may be such as to overcome the action of spring 36.

The handle 18 is maintained in its inoperative position as in Fig. 1 by a double ball catch arrangement 50, this comprising a pair of balls spring pressed apart and fitting in a bore 52 of the handle so that the balls yieldingly press upon walls 54 of the pipe part 12 forming a slot for the reception of the handle 18.

In the operation of the device, after a pipe full has been smoked, it is merely necessary to grasp the fins on the handle 18, bring the handle down, and move it in an upward direction to clear the pipe bowl. If cleaning element 38 tends to stick, it is flexible enough to be rammed through the bowl without injury, and as seen in Fig. 1, it is clear that the element 38 is a little smaller in

diameter than the bowl of the pipe to allow a desired degree of caking.

The smoke will pass down past cover 34, through the holes 32, and into the well 26, and of course the same is true of moisture which is, however, kept away from plunger 22 by the cover 34 and shield 42. This shield is not in all cases necessary, but it improves the cleanliness and sanitation of the pipe. Moisture and detritis will be caught in the well 26 below the level of the smoke hole 56. Another protection against moisture entering the bushing and impinging on plunger 22 resides in the collar 58 which acts as a barrier. This collar may be integral with cover 34 and has a V-section, the apex of which points downwardly. It will be clear that this invention provides a sanitary and clean ash ejector which will always remain clean due to the cover 34, shield 42, and other details of the construction of the device.

Having thus described our invention and the advantages thereof, we do not wish to be limited to the details herein disclosed otherwise than as set forth in the claims, but what we claim is:

1. A pipe comprising a pipe body, a stem therefor, said body having a hollow portion, an upstanding wall forming a central bore and a surrounding well in the hollow portion, a slotted threaded head on the wall, a bowl threaded thereon and seating on the pipe body, a plunger in the bore, a bowl cleaning element on the plunger above the wall, and a jointed handle for the plunger to reciprocate the bowl cleaning element.

2. A pipe comprising a pipe body, a stem therefor, said body having a hollow portion, an upstanding wall forming a central bore and a surrounding well in the hollow portion, a slotted threaded head on the wall, a bowl threaded thereon and seating on the pipe body, a plunger in the bore, a bowl cleaning element on the plunger above the wall, and a jointed handle for the plunger to reciprocate the bowl cleaning element, the latter being slotted and flexible and of a diameter less than that of the bowl.

3. A pipe comprising a pipe body, a stem therefor, said body having a hollow portion, an upstanding wall forming a central bore and a surrounding well in the hollow portion, a slotted threaded head on the wall, a bowl threaded thereon and seating on the pipe body, a plunger in the bore, a bowl cleaning element on the plunger above the wall, a jointed handle for the plunger to reciprocate the bowl cleaning element, and a cover on the plunger to exclude moisture therefrom when the plunger is retracted, said cover being secured to the plunger just beneath

the bowl cleaning element and seating on the wall to close the well when the plunger is in retracted condition.

5. A pipe comprising a body provided with a well, an annular wall rising from the bottom of the well having a bore, a plunger in the bore, a flexible cover fixed on the plunger extending downwardly to the bottom of said bore, a bowl mounted on the body, a pipe cleaning element on the plunger above the cover, and a jointed handle to reciprocate the plunger.

15 6. A pipe comprising a body provided with a well, an annular wall rising from the bottom of the well having a bore, a plunger in the bore, a flexible cover fixed on the plunger extending downwardly to the bottom of said bore, a bowl mounted on the body, a pipe cleaning element on the plunger above the cover, and a jointed handle to reciprocate the plunger, said handle 20 being retractable within a slot in the underside of the body, and spring pressed balls to yieldingly retain the same therein.

25 7. A pipe comprising a pipe body having an annular well, an annular wall having a bore positioned in said well, a bowl secured to said wall in seated relation to the body, a plunger in said body and bore, a bowl cleaning element on said plunger, there being a smoke hole in the body above the bottom of the well, means to manipulate the plunger to reciprocate the cleaning element to clean the bowl, a spring about the plunger to center the same, a stretchable cover for the spring, said cover being secured to the plunger adjacent the cleaning element and to the pipe body adjacent the bottom of the bore to prevent entry of moisture to the plunger.
